STREET LIGHTING STANDARD

Paul A. Millerbernd, Winsted, Minn.

Application April 19, 1954, Serial No. 30,079

Term of patent 14 years

(Cl. D48—31)

To all whom it may concern:

Be it known that I, Paul A. Millerbernd, a citizen of the United States, residing at Winsted, State of Minnesota, have invented a new, original, and ornamental Design for Street Lighting Standard, of which the following is a specification, reference being had to the accompanying drawing, forming a part hereof.

Fig. 1 is a side elevational view of a street lighting standard showing my new design;

Fig. 2 is a top plan view thereof;

Fig. 3 is a cross sectional view to a larger scale taken on line 3—3 of Fig. 1; and

Fig. 4 is a fragmentary side elevational view to a larger scale.

I claim:

The ornamental design for street lighting standard, substantially as shown.
